MUFFLER WITH EXPANSION CHAMBER AND
TRANSVERSE PERFORATED BAFFLES

Edward Albert Kliewer, Sr., Longview, Tex.

Application June 9, 1947, Serial No. 753,551

5 Claims. (Cl. 181—44)

1

The invention relates generally to sound controlling devices and primarily seeks to provide a novel muffler device adapted for use on motor cars or the like embodying internal combustion engines; said muffler being exceedingly simple in structure and efficient in the silencing of the noises normally resulting from the exhausting of burnt gases from said engines.

An object of the invention is to provide a muffler structure that can be manufactured inexpensively because of the small number of simple parts of which it is composed; and in which means are provided for permitting rapid and yet controlled expansion of the exhaust gases as they enter the muffler in such manner as will assure rapid dissipation of heat without any appreciable setting up of back pressure at the engine to which the muffler is attached; thereby to assure cooler and more economical running of the engine, and also long life of both the engine and the muffler structure.

In its more detailed nature the invention resides in providing an improved muffler structure of the character stated in which are provided an outer imperforate drum or shell having an inlet cone and an outlet cone secured thereto, an inner perforate shell spaced within the outer shell and having a perforated end closure disposed adjacent the entrance into the outlet cone and an annular closure wall disposed adjacent the juncture of the inlet cone and the outer shell; an inlet tube having a diameter approximately half that of the inner shell and extending through the inlet cone and opening abruptly into the inner shell; an inwardly directed cone ring baffle disposed approximately in the entrant end of the outlet cone; a star baffle disposed transversely of and in the outlet cone; and an outlet tube extending away from the outlet cone and having a diameter at least equal to the diameter of the inlet tube.

With the above and other objects in view that will hereinafter appear, the nature of the invention will be more clearly understood by reference to the following detailed description, the appended claims, and the several views illustrated in the accompanying drawings.

In the drawings:

Figure 1 is a central longitudinal sectional view illustrating the improved muffler.

Figure 2 is a vertical cross section taken on the line 2—2 on Figure 1 looking toward the inlet end.

Figure 3 is a vertical cross section taken on the line 3—3 on Figure 1 looking toward the outlet

2

end; the cone ring baffle outlet being shown in dotted lines.

Figure 4 is a vertical cross section taken through the outlet cone on the line 4—4 on Figure 1 and looking toward the star baffle.

In the example of embodiment of the invention herein disclosed the improved muffler structure includes an outer imperforate drum or shell 5 having an inlet cone 6 preferably weld-secured thereto as at 7, and an outlet cone 8 preferably weld-secured thereto as at 9.

An inner shell 10 is mounted in spaced relation within the outer shell and has its wall structure perforated as at 11. The inner shell 10 is closed at its inlet end by an annular wall or ring 12 which is preferably weld-secured to the shell end as at 13. A convex wall 14 closes the outlet end of the inner shell 10, the same being perforated as at 15 and preferably weld-secured to the shell end as at 16 and equipped with radially extended spider arm extensions 17 which are weld-secured to the outer shell as at 18.

An inlet tube 19 extends through the inlet end of the inlet cone 6 and opens abruptly into the inner shell 10 through the end closure ring 12. The inlet tube 19 preferably is weld-secured as at 20 to the inlet cone 6, and as at 21 to the end closure ring 12. The inlet tube 19 may be slotted or split as at 22 at its entrant end in order to facilitate the securing of the muffler to the engine exhaust pipe (not shown).

A cone ring baffle 23 is weld-secured as at 24 approximately at the entrance into the outlet cone 8, and a star shaped flat baffle 25 traverses the outlet cone 8, intermediately of the ends thereof, the same being weld-secured as at 26 to said outlet cone. The star shaped flat baffle preferably is perforated as at 27.

An outlet tube 28 is weld-secured as at 29 to the discharge end of the outlet cone 8, and said outlet tube has a diameter at least as great as that of the inlet tube 19.

In use, the receiving end of the inlet tube 19 of the muffler structure is attached to the engine exhaust pipe as by clamping at 22, and the exhaust gases passing through the tube 19 expand abruptly into the relatively large inner shell 10, expanding through the carefully proportioned perforations 11 into the space surrounding the inner shell 10. It will be apparent that some of the gases coming against the convex end wall 14 of the inner shell 10 may pass directly through the apertures 15 into the cone baffle ring 23. The gases which expand and escape through the inner shell perforations 11 pass endwise through the

outer shell 5 into the cone ring baffle 23 and through the restricted passage therethrough into the outlet cone 8. The gases thus escaping through the restricted cone ring baffle 23 come against the flat star baffle 25, some thereof passing directly through the baffle apertures 27, but the major portion thereof passing about the star baffle through the spaces intervening the same and the surrounding wall of the outlet cone 8, said gases ultimately escaping through the outlet tube 28. By reason of the proportioning of the parts as herein described, the inner shell 10 being approximately twice the diameter of the inlet tube 19, the exhaust gases expand suddenly into the inner shell in a manner for greatly facilitating heat dissipation and the desired reduction of exhaust noises. The final expansion and exhausting of the gases is controlled by the passage thereof through the shell perforations 11 into the space surrounding the inner shell, and through the cone ring baffle 23 and about the flat star baffle 25 into the outlet tube 28. This controlling of the exhausting gases is accomplished without setting up any objectionable back pressure at the engine with which the muffler is connected, and it has been found that this improved muffler structure provides not only for the desired muffling of sound but also dissipates heat so rapidly as to provide for long life of the muffler structure and also for a longer life of the motor connected with said muffler structure.

It is to be noted that the cone ring baffle 23 has a center opening which is greater in diameter than the diameter of the inlet tube 19, thus providing relief at this point, and the exhausting gases coming through the center opening in the cone baffle ring 23 strike the center of the flat star baffle 25 which spreads the exhausting gases through the four outlets provided between the outer edges of the baffle 25 and the surrounding wall of the tapering frusto-cone 8. The four outlets about the flat star baffle 25 are approximately equivalent in area to the area of the center opening in the cone ring baffle 23.

It is well understood that larger sizes of internal combustion engines have larger sizes of exhaust outlets in the exhaust manifolds. It is also to be understood that the holes 11 in the inner sleeve 10 of my improved muffler structure may vary in number and size accordingly as the exhaust outlets of the engines with which the muffler structures are to be used vary, the combined area of the holes being at least slightly in excess of the area of the engine exhaust outlet so as to avoid all objectionable back pressure.

The use of the simple, single perforated sleeve 10 makes it easy to provide the desired back pressure release and noise reduction for each engine design with which the muffler structure is to be installed. In initially testing a muffler structure for adaptability with a particular design of engine so as to set the production standards for use with said design, the sleeve 10 may be provided with a greater number of holes 11, or with larger holes 11 if the tests show that an objectionable amount of back pressure is being encountered. When the tests show that objectionable noise is being encountered, the number or size of the holes 11 will be correspondingly reduced. It will be readily apparent that the provision of the single perforated sleeve greatly facilitates this establishment of efficiently operating standards.

While one form of the invention has been

shown for purposes of illustration, it is to be clearly understood that various changes in the details of construction and arrangement of parts may be made without departing from the spirit and scope of the invention as defined in the appended claims.

I claim:

1. An engine exhaust silencing muffler comprising, a generally cylindrical outer shell having an entrant end and a discharge end, a tapering frusto-conical extension at said discharge end, an inner shell concentrically spaced within the outer shell perforated about the whole of its circumference and having an end closure disposed adjacent the entrance into the tapering frusto-cone and an annular closure wall extending inwardly at its entrant end, an inlet tube having a diameter approximately half that of the inner shell opening abruptly through said annular closure wall into the inner shell, an inwardly directed cone ring baffle having an outlet end extending into the entrant end of the tapering frusto-cone, a star baffle disposed transversely of the tapering frusto-cone intermediately of the ends thereof and beyond the outlet end of said cone ring baffle, and a discharge tube extending away from the tapering frusto-cone and having a diameter at least as great as that of the inlet tube.
2. An engine exhaust silencing muffler comprising, a generally cylindrical outer shell having an entrant end and a discharge end, a tapering frusto-conical extension at said discharge end, an inner shell concentrically spaced within the outer shell perforated about the whole of its circumference and having an end closure disposed adjacent the entrance into the tapering frusto-cone and an annular closure wall extending inwardly at its entrant end, an inlet tube having a diameter approximately half that of the inner shell and opening abruptly through said annular closure wall into the inner shell, an inwardly directed cone ring baffle having an outlet end extending into the entrant end of the tapering frusto-cone, said end closure having perforations therein opening into said cone ring baffle, a star baffle disposed transversely of the tapering frusto-cone intermediately of the ends thereof and beyond the outlet end of said cone ring baffle, and a discharge tube extending away from the tapering frusto-cone and having a diameter at least as great as that of the inlet tube.
3. An engine exhaust silencing muffler comprising, a generally cylindrical outer shell having an entrant end and a discharge end, a tapering frusto-conical extension at said discharge end, an inner shell concentrically spaced within the outer shell perforated about the whole of its circumference and having an end closure disposed adjacent the entrance into the tapering frusto-cone and an annular closure wall extending inwardly at its entrant end, an inlet tube having a diameter approximately half that of the inner shell and opening abruptly through said annular closure wall into the inner shell, an inwardly directed cone ring baffle having an outlet end extending into the entrant end of the tapering frusto-cone, said end closure being convex and perforated and including spider arm extensions serving to space the inner shell within the outer shell, a star baffle disposed transversely of the tapering frusto-cone intermediately of the ends thereof and beyond the outlet end of said cone ring baffle, and a discharge tube extending

away from the tapering frusto-cone and having a diameter at least as great as that of the inlet tube.

4. An engine exhaust silencing muffler comprising, a generally cylindrical outer shell having an entrant end and a discharge end, a tapering frusto-conical extension at said discharge end, an inner shell concentrically spaced within the outer shell perforated about the whole of its circumference and having an end closure disposed adjacent the entrance into the tapering frusto-cone and an annular closure wall extending inwardly at its entrant end, an inlet tube having a diameter approximately half that of the inner shell and opening abruptly through said annular closure wall into the inner shell, an inwardly directed cone ring baffle having an outlet end extending into the entrant end of the tapering frusto-cone, a star baffle disposed transversely of the tapering frusto-cone intermediately of the ends thereof and beyond the outlet end of said cone ring baffle, said star baffle being flat and perforated and providing spaces between edge portions thereof and the surrounding portions of the tapering frusto-cone, and a discharge tube extending away from the tapering frusto-cone and having a diameter at least as great as that of the inlet tube.

5. An engine exhaust silencing muffler comprising, a generally cylindrical outer shell having an entrant end and a discharge end, a tapering frusto-conical extension at said discharge end, an inner shell concentrically spaced within the outer shell perforated about the whole of its circumference and having an end closure dis-

posed adjacent the entrance into the tapering frusto-cone and an annular closure wall extending inwardly at its entrant end, an inlet tube having a diameter approximately half that of the inner shell and opening abruptly through said annular closure wall into the inner shell, an inwardly directed cone ring baffle having an outlet end extending into the entrant end of the tapering frusto-cone, said end closure being convex and perforated and including spider arm extensions serving to space the inner shell within the outer shell, a star baffle disposed transversely of the tapering frusto-cone intermediately of the ends thereof and beyond the outlet end of said cone ring baffle, said star baffle being flat and perforated and providing spaces between edge portions thereof and the surrounding portions of the tapering frusto-cone, and a discharge tube extending away from the tapering frusto-cone and having a diameter at least as great as that of the inlet tube.
